UNITED STATES PATENT OFFICE.

YUSKE MIYASAKI, OF KANSAS CITY, MISSOURI.

CAST TRUCK BOLSTER.

Application filed March 28, 1925. Serial No. 19,107.

To all whom it may concern:

Be it known that I, YUSKE MIYASAKI, a subject of the Emperor of Japan, residing at Kansas City, in the county of Jackson and State of Missouri, have invented certain new and useful Improvements in Cast Truck Bolsters, of which the following is a specification, reference being had to the accompanying drawings.

10 This invention relates to certain improvements in cast truck bolsters and is primarily an improvement on the bolster disclosed in my reissue Patent No. 14,307, dated May 29, 1917, and it is an object of the present invention to provide a bolster wherein a plurality of longitudinally extending spaces is formed along the under side of the bottom chord of the bolster whereby the cooling rate of the bottom chord during the casting 20 process may be made equal to that of the other parts of the bolster to thus minimize casting defects and shrinkage strain and to simplify the molding process.

Another object of the invention is to 25 provide a bolster of this kind constructed and molded in a manner whereby the bolster is produced with a homogeneous grain of metal throughout.

Another object of the invention is to 30 construct a bolster of this kind wherein a portion of the metal, which would be used to form the part near the neutral axis of the vertical section of the bolster is employed to form the inner flanges in the top chord, and balance of said metal is added to the bottom chord to increase the section modulus of the section and thereby produce greater vertical strength.

With the addition of metal to the bottom 40 chord distributed as far as possible from the neutral axis within the limited depth of the bolster in order to obtain maximum vertical strength will result in increased thickness of the bottom chord to such an extent that ordinarily the bottom chord will be in liquid state when solidification begins in other parts of the bolster on account of excessive difference in thicknesses and the bottom chord, caused by earlier contraction 45 of metal forming the other parts, will be subjected to excessive shrinkage strain which cannot be removed by an annealing process.

It is an object of the invention to provide 50 spaces in the bottom chord whereby the heat radiating surface will be greatly increased and therefore making it possible to have the

rate of cooling of the bottom chord equal to that of the other parts of the bolster, resulting in a casting having a homogeneous grain of metal which will give increased 60 strength to withstand impact compared with a casting having uneven crystallization of metal due to unequal rate of cooling, such equalization of the cooling action also reducing to a minimum the shrinkage strain 65 at junctures and liability of casting defects.

The invention consists in the details of construction and in the combination and arrangement of the several parts of my improved cast truck bolster whereby certain 70 important advantages are attained and the device rendered simpler, less expensive and otherwise more convenient and advantageous for use, as will be hereinafter more 75 fully set forth.

The novel features of my invention will hereinafter be definitely claimed.

In order that my invention may be the better understood, I will now proceed to describe the same with reference to the accompanying drawings, wherein:

Figure 1 is a view in side elevation of a bolster constructed in accordance with an embodiment of my invention;

Figure 2 is a view in bottom plan of one 85 longitudinal half of the bolster as comprised in Figure 1;

Figure 3 is a sectional view taken substantially on the line 3—3 of Figure 1;

Figure 4 is a sectional view taken substantially on the line 4—4 of Figure 1;

Figure 5 is a fragmentary view in elevation of the central portion of the bottom chord and the lower portion of the vertical truss illustrating a slightly modified form 95 of invention;

Figure 6 is a fragmentary view in bottom plan of the structure as illustrated in Figure 5;

Figure 7 is a view in top plan of the bolster as comprised in Figure 1.

As particularly illustrated in Figures 1 to 4 inclusive and Figure 7, 1 denotes the top chord member and 2 the bottom chord member. At their opposite ends the top and bottom chord members 1 and 2 are integrally connected together by the vertical walls 3 and the outer faces of these vertical walls have the usual guide flanges 4 formed thereon and the end portions of the upper chord member 1 are provided with the bearings 5. The top chord member 1 and the

bottom chord member 2 are integrally connected and braced to resist vertical strains by a central tubular truss 6.

The top chord member 1 is constructed in substantially the same manner as disclosed in my reissue Patent No. 14,307, dated May 29, 1917, including the inner vertical flanges 7 and the outer vertical flanges 8.

As is particularly illustrated in Figure 3, the bottom chord 2 is of greater thickness than that of the top chord 1 due to the fact that a portion of the metal, which would be used to form a part near the neutral axis of the vertical section of a bolster, is added to the bottom chord whereby greater vertical strength will be obtained on account of the section modulus of the section being increased.

The width of the bottom chord 2 and the overall depth of the bolster are limited on account of the standard construction of a truck to which the bolster is to be applied, and the addition of metal to the bottom chord, as far from the neutral axis as possible within the limited depth of the bolster in order to obtain maximum vertical strength, will result in the thickness of the bottom chord 2 being increased to such an extent that the bottom chord 2 will be, during the molding process, in liquid state when solidification begins in the other parts of the bolster on account of the excessive difference in thicknesses and ordinarily the bottom chord, caused by the earlier contraction of the metal forming the other parts, will be subjected to excessive shrinkage strain which cannot be removed by an annealing process.

The bottom chord 2 is formed with the under surface provided therealong with the separated ribs 9 providing therebetween the spaces 10 whereby the heat radiating surface of the bottom chord is greatly increased and therefore making the rate of cooling of the bottom chord equal to that of the other parts of the bolster. Equal rate of cooling on all parts of the bolster will produce a homogeneous grain of metal which will give greater strength to withstand impact in comparison with a bolster having uneven crystallization of metal due to an unequal rate of cooling. This equal rate of cooling will also reduce to a minimum the shrinkage strain at junctures and liability of casting defects.

It is considered to be of decided advantage to cast the bolster with the chord 2 at the bottom of the mold so that when metal is poured into the mold the filling starts at the lowest point of the bottom chord 2 and gradually rises toward the ends of the bolster.

To properly equalize the rate of cooling in the bottom chord and also to decrease the amount of metal in proportion to the decreased vertical strength required toward the ends, the thickness of the ribs 9 is gradually

reduced toward the ends of the bolster and meeting the top chord with even thickness.

As particularly illustrated in Figures 1 and 2, the ribs 9 extend outwardly from a point adjacent to the pillar whereas in Figures 5 and 6, I illustrate a slightly modified form of my invention wherein said ribs 9' are continuous along the underside of the bottom chord 2' and which arrangement is possible when there is sufficient clearance between the low point A of the bolster and the part of the truck to which the bolster is applied.

In the present embodiment of my invention it is to be understood that the flanges 7 and 8 are employed for the same purposes as particularly disclosed in my reissue patent hereinbefore referred to, the efficiency of the bolster being further materially increased by the particular forms of bottom chord members herein particularly set forth. Since the pattern is drawn upwardly, the molding process is greatly simplified by providing the ribs and spaces on the under side of the bottom chord member and while I have illustrated in the accompanying drawings such ribs and spaces as extending longitudinally of the bottom chord member, it is to be understood that said ribs may be united crosswise where it is deemed necessary to provide such reinforcement.

From the foregoing description it is thought to be obvious that a cast truck bolster constructed in accordance with my invention is particularly well adapted for use by reason of the convenience and facility with which it may be assembled, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A cast truck bolster comprising a top chord member and a bottom chord member, a central truss connecting said chord members, said chord members meeting at the ends of the bolster, said bottom chord having ribs provided on a face thereof affording spaces therebetween.

2. A cast truck bolster comprising a top chord member and a bottom chord member, a central truss connecting said chord members, said chord members meeting at the ends of the bolster, said bottom chord having ribs provided on a face thereof affording spaces therebetween, said ribs and intervening spaces being provided on the underside of the bottom chord member.

3. A cast truck bolster comprising a top chord member and a bottom chord member,

a central truss connecting said chord members, said chord members meeting at the ends of the bolster, said bottom chord having ribs provided on a face thereof affording spaces therebetween, said top chord member having downwardly disposed flanges at the marginal portions thereof.

4. A cast truck bolster comprising a top chord member and a bottom chord member,

a central truss connecting said chord members, said chord members meeting at the ends of the bolster, said bottom chord having a plurality of longitudinally extending ribs provided on a face thereof affording spaces therebetween.

In testimony whereof I hereunto affix my signature.

YUSKE MIYASAKI.
